SNOWPLOW

Filed July 2, 1928

FIG. 1.

FIG. 2.

INVENTOR
J. A. LITT.

BY *J. A. Litt*

ATTORNEYS.

UNITED STATES PATENT OFFICE.

JAMES ALEXANDER LITT, OF STRATFORD, ONTARIO, CANADA.

SNOWPLOW.

Application filed July 2, 1928. Serial No. 289,786.

My invention relates to improvements in snow plows, of the type disclosed in my Canadian application Serial No. 334,122, filed February 21st, 1928, and United States application Serial No. 256,387, filed February 23rd, 1928, and the object of the present invention is to provide a more rigid and positive means for adjusting the angular position of the plow in relation to the road surface, and also to provide simple means whereby the snow plow may be readily elevated from the road surface and carried by an undercarriage when it is desired to transport the plow from place to place, and it consists essentially of the arrangement and construction of parts as hereinafter more particularly explained.

Fig. 1 is a perspective view of my plow.

Fig. 2 is a longitudinal sectional view through the plow.

In the drawing like characters of reference indicate corresponding parts in each figure.

The body of the plow consists of a platform 1 adapted when in the operative position to incline upward from its cutting or forward edge which bears on the surface of the road. The rear edge of the platform is provided with a V-shaped recess 1^x along the edges of which walls 2 and 3 extend upwardly to form the plow point proper which is V-shaped in form, the walls being provided at their upper edges with upwardly extending flanges 2^x and 3^x.

4 is a deflecting member which is pivotally supported at its inner end upon a rod 5 journaled at its lower end in the platform 1 and at its upper end in a bearing plate 6 secured to the flanges 2^x and 3^x and extending forwardly of the apex of the plow point.

At each side of the platform 1 adjacent its forward edge is located a standard member 6^x, the standard members 6^x being connected at their upper ends by a cross bar 7 which is preferably in the form of an angle bar, the ends of which are connected by inclined braces 8 and 9 to the plates 6.

10 is an adjusting bolt which may be in the form of a rod extending downward through the horizontal flange of the angle bar 7 through the deflecting member 4 into any one of the series of orifices 11 formed in the member 1. By this means the angular position of the deflecting member 4 may be adjusted as required.

In the recess formed in the rear edge of the platform 1 and by the walls 2 and 3 is located

a rectangular frame 12, the side bars of which are formed by angle bars which provide vertical channels in which a supplemental vertically adjustable frame 13 is movable.

The inwardly extending flanges of the angle bars 12 are provided with a vertical series of orifices 12^x and the adjacent flanges of the frame 13 with an orifice 13^x through which a pin 14 extends, such pin passing through any one of the orifices 12^x to adjust the supplemental frame 13 to any desired position.

15 are push bars which are pivoted at 16 to any suitable point beneath the platform 1 adjacent the front end thereof. The forward end of the push bars extend through recesses 16^x in the supplemental frame 13 and are pivotally connected at 17 to the push bars 18 of a tractor or other suitable device by which the snow plow is operated.

In order to adjust the angular position of the snow plow in relation to the road surface all it is necessary to do is to withdraw the pins 14 and move the supplemental frame 13 within the angle bars 12 to the desired position, and then reinsert the pin 13^x.

19 and 20 are bearing standards preferably carried by the flanges 2^x and 3^x at each side of the V-shaped recess hereinbefore referred to. 21 is a shaft turnably mounted in the bearings 19 and 20 and on which is secured a winding drum 22. 23 is a plate or frame provided intermediately of its length at each side with lugs 24 which are pivoted at 25 in brackets 26 secured to the lower face of the platform 1. 27 is an axle carried at the forward end of the plate or frame 23 and on which are mounted carrier wheels 28. 29 is a cable or chain secured at its lower end adjacent the rear end of the plate or frame 23. The upper end of the cable or chain 29 is wound around the drum 22 and is secured thereto. 30 is a bevelled gear secured to the shaft 21. 31 is an operating shaft provided on its inner end with a bevelled gear 32 meshing with the bevelled gear 30. The inner end of the shaft is preferably carried in a bracket 33 which is swung upon the shaft 21 as indicated at 34 and 35. The opposite end of the shaft 31 extends through the wall 36 of a cab of a tractor or other device for operating the snow plow and is provided with a hand wheel 37.

By turning the hand wheel 37 the shaft 21 is rotated by means of the gears 32 and 30 rotating the drum 22 and winding the cable 110

or chain 29 thereon. By this means the plate or frame 23 is drawn upward around its pivot 25 carrying the carrier wheels 28 into contact with the road surface and by continuation of the upward pull exerted by the chain or cable 29 the pressure of the carrier wheels 28 against the road surface lifts the snow plow bodily upward carrying the parts into the dotted position shown in Fig. 2, raising the forward edge of the platform 1 clear of the road surface so that the plow may be transported easily from place to place.

When it is desirable to continue the plowing operation the drum 22 is turned in the opposite direction so as to slacken the chain or cable, permitting the snow plow to re-engage the snow surface.

It will be noted that the plate or frame 23 is so mounted that the rear end of the plate counter balances the weight of the forward end and the wheels 28 carried thereby and therefore when the undercarriage is not in operation supporting the snow plow the plate assumes a downwardly inclined position to-

wards its rear edge, holding the wheels 28 clear of the ground.

From this description it will be seen that I have devised very simple and positive means whereby the angular position of a plow may be readily adjusted whenever desired, and at the same time I provide simple means whereby the snow plow can be lifted bodily from its operative position to be carried by an undercarriage so that it may be readily moved from place to place.

What I claim as my invention is:

In a snow plow, the combination with an inclined platform having a forward cutting edge and plow members carried upon the platform, of opposing vertical guides located adjacent each side of the plow, a frame slideable within the guides, means for securing the frame in any position to which it is adjusted within the guides, and push bars pivotally connected at their forward ends to the platform and supported at their rear ends upon the adjustable frame.

JAMES ALEXANDER LITT.
